(57) **CLAIM**

The ornamental design for an air delivery manifold, as shown and described.

DESCRIPTION

FIG. 1 is a top perspective view of an air delivery manifold showing the new design;

FIG. 2 is a bottom perspective view thereof;

FIG. 3 is a top plan view thereof;

FIG. 4 is a bottom plan view thereof;

FIG. 5 is a front view thereof;

FIG. 6 is a rear view thereof;

FIG. 7 is a right side view thereof; and,

FIG. 8 is a left side view thereof.

The broken lines in the Figures are included for the purpose of illustrating environment and form no part of the claimed design.
